Attorney.

UNITED STATES PATENT OFFICE.

FRED GLOVER, OF CAULFIELD, VICTORIA, AUSTRALIA.

JET AND SPRAY NOZZLE.

Application filed January 13, 1927, Serial No. 180,910, and in Australia January 11, 1926.

This invention relates to a combined jet and spray nozzle or fitting for attachment to garden hose or other water pipes and the like. More particularly the invention refers to that class of device whereby the stream of water passing from the nozzle may be caused to issue either as a jet or in the form of a fine spray.

In existing devices of the above class the spray is usually formed by means of a conical member such as a needle valve placed in the path of the liquid and adjustable so that the water stream may be spread sidewardly as it leaves the nozzle or may be concentrated to form a jet.

An objection to such existing devices is that the spray projected from the nozzle is usually "hollow" or of annular form so that when the device is used for instance in an upright position to act as a sprinkler, the water falls to the ground in a ring, the area within which is not watered.

The primary object of the present invention is to overcome the abovementioned objection and to provide an improved nozzle whereby the liquid stream may be readily varied from a relatively large and powerful jet to a dense spray in which the water is evenly distributed over the whole central area within the marginal limits of the spray.

The invention also aims at providing a simple and highly efficient construction whereby the foregoing improved results are obtained and in addition the water stream may, when desired, be concentrated into an extremely narrow jet so that it is projected for a relatively long distance even under conditions of low water pressure.

Referring to the drawings which form part of this specification:—

Figure 1 is a side elevation showing the invention fitted to the end of a hose director.

Figure 2 is a longitudinal section of the improved device showing the parts in position to eject the liquid only through the small central bore of the control valve.

Figure 3 is a part sectional elevation showing the parts in position to eject both a central jet and a sidewardly extending spray of water.

Figure 4 is a part sectional elevation showing the parts in position to eject only the main central jet of water to the exclusion of the sidewardly extending spray.

Figure 5 is a cross section on line A—A of Figure 3.

Figure 6 is a cross section on line B—B of Figure 2.

Figure 7 shows the invention in use as an upright sprinkler on a suitable stand or support.

Figure 8 shows the invention applied to an inclined director or nipple on a horizontal water supply pipe.

A device in accordance with the invention comprises a hollow metallic fitting or socket member 2 the inner or rear end of which is internally screw threaded as at 3, for engagement with the usual screwed hose director 4 or any other suitable conduit through which liquid is supplied to the nozzle. A liquid inlet passage 6 is formed centrally through the socket member 2 and its outer or forward end is externally threaded to 75 detachably receive a valve carrying member 7.

The valve carrying member 7 has a longitudinal central passageway 8 which slidably accommodates the stem of a valve 9 of a construction which will be hereinafter described. The front end of said valve stem may be externally beveled or chamfered as at 10. Formed through the front portion of the valve carrying member, which constitutes a transverse partition between the valve chamber 12 and the discharge orifice 18 hereinafter described, are longitudinal passages 11 which are tangentially inclined or of somewhat spiral formation so that liquid passing through them is given a whirling motion. Rearwardly of the valve chamber 12 the member 7 is internally screw threaded to engage the external thread of the socket member 2 which is provided with a shoulder 13 against which the rear extremity of said member 7 may abut.

The valve carrying member 7 is also screw threaded externally as at 14 to receive an internal thread of a longitudinally adjustable sleeve member 16 which is completely open at its inner end, and is partially closed at its outer end by a front transverse wall 17 having formed therethrough a central water discharge orifice 18. The edge of this orifice is preferably of tapered or conical formation so that it diverges outwardly as shown.

A valve seating 19 is formed in the front face or end of the socket member 2 to en-

gage the rear conical face 23 of an enlarged head on the aforementioned valve 9. The stem of this valve is of hollow or tubular form and has adjacent its inner end a series of radial ports 22 which are adapted to provide communication between the internal passage 20 of said tubular valve stem and the valve chamber 12 formed between the valve carrying member 7 and the socket member 2.

A front face or shoulder 24 of the valve head is adapted to engage a corresponding seating 26 formed at the inner end of the central passage 8 through the valve carrying member 7 whereby communication between the inlet passage 6 and the ports 22 of the tubular valve stem may be cut off when desired as indicated in Figure 3.

For certain purposes, particularly when the device is to be used as a nozzle for garden hose a narrow central bore or aperture 27 is preferably formed through the head of the valve 9 so that the inlet passage 6 is in permanent communication with the internal passage 20 through the valve stem. In some cases the passage 27 may be eliminated, so that when the parts are in the position seen in Figure 2 the discharge of liquid is entirely cut off.

30 The internally threaded rear end of the adjusting sleeve member 16 is preferably screwed onto a threaded ring or lock nut 28 which freely but closely encircles the socket member 2 and prevents leakage as well as serving as a stop to prevent the sleeve from being entirely withdrawn from the fitting.

35 The socket member 2, the nut 28 and the sleeve 16 may be each provided with milled or like external faces as shown to facilitate 40 assemblage, adjustment and dismantling of the parts.

With the device in use the discharge of liquid may be restricted to a narrow but elongated jet by moving the adjusting sleeve 45 16 to its innermost position as seen in Figure 2 so that owing to the engagement of the sleeve wall 17 with the front end of the valve stem the rear face 23 of the valve head contacts with the seating 19 formed at the front end of the socket member 2, thus cutting off the water inlet passage 6 from the 50 passages 11 and the radial ports 22 of the valve. The water is thus permitted to issue only through the small central aperture 27 which is always open and enables a long 55 narrow jet of liquid to be delivered even with a very low water pressure. With the parts in this adjusted position the device is adapted for light spraying at a distance and is particularly suitable for watering 60 young plants and the like. In cases where the central aperture 27 is omitted it will be evident that with the parts adjusted as in Figure 2 the discharge of water from the nozzle will be entirely cut off.

When it is desired to project the liquid in a larger jet the adjusting sleeve 16 is screwed outwardly so that the valve head is forced by the water pressure to leave the seating 19 of the socket member 2. By positioning the sleeve 16 as seen in Figure 4 such outward movement of the valve is arrested before the shoulder 24 of the valve head engages the seating 26 at the inner face of the valve carrying member 7 so that the liquid passes through the radial ports 22 as well as the aperture 27 into the internal passage 20 of the valve stem and thence out through the discharge orifice 18 in the end wall 17 of the adjusting sleeve. In this position the outer end of the valve stem abuts against the sleeve wall 17; and as said stem is of greater diameter than the discharge orifice 18 and is concentrically aligned therewith, the passages 11 are cut off from the discharge orifice so that a straight jet of water from the hollow valve stem is produced.

In either of the positions illustrated in Figures 2 and 4 the bevelled front edge 10 of the valve stem engages within and against the inner edge of the discharge orifice 18, thus positively preventing side play of the valve and the escape of water except by way of the valve passage 20.

Upon screwing the adjusting sleeve further outwardly as seen in Figure 3, the water pressure forces the valve head against its seating 26 at the inner face of the valve carrying member 7 so that the radial ports 22 are closed and water is admitted into the valve stem only through the small central aperture 27. The end wall 17 of the adjusting sleeve is now clear of the adjacent end of the valve stem so that the discharge orifice 18 is placed in communication with the inclined passages 11 in the valve carrying member. As the water passes through these latter passages it is subjected to a whirling action; and as it issues from the outer end of the passages 11 it impinges against the sleeve wall 17, whereby it is caused to combine with the jet passing from the central aperture 27 and to issue from the discharge orifice 18 in the form of a finely atomized sidewardly extending spray wherein the water is effectively distributed over the whole central area within the marginal limits of the spray as previously mentioned. By manipulating the sleeve 16 so as to vary the distance between the wall 17 and the front end of the valve stem the angle and width of the spray may be readily altered according to requirements.

Having now described my invention what I claim as new and desire to secure by Letters Patent is:—

1. An improved jet and spray producing nozzle or device comprising a valve having a hollow stem adapted to slide longitudinal-

ly in the direction of the liquid flow under the pressure of the liquid passing through the nozzle, said valve having an inlet opening to said stem at its rear end; an inlet 5 passage aligning with said inlet opening and controlled by said valve; a manually operable adjusting sleeve enclosing said valve, said sleeve having a discharge orifice formed in alignment with the valve stem through a transverse front wall which is adapted to engage and move said stem in the opposite direction and to retain the valve in various adjusted positions against the action 10 of the liquid pressure; and a valve-carrying member embodying a partition spaced from said transverse wall and having an opening wherein the valve stem is slidably arranged and also have a series of liquid passages, said valve-carrying member having an internal 15 chamber behind said partition into which said inlet passage and said liquid passages open, communication between said liquid passages and said discharge orifice by way of such space being cut off by the engagement 20 of the front end of the valve stem with said transverse wall.

2. An improved jet and spray producing nozzle or device comprising a valve having a hollow stem adapted to slide longitudinally in the direction of the liquid flow under the pressure of the liquid passing through the nozzle, said valve having an inlet opening to said stem at its rear end; an inlet passage aligning with said inlet opening and controlled by said valve; a manually operable adjusting sleeve enclosing said valve, said sleeve having a central discharge orifice formed in alignment with the valve stem through a transverse front wall which is adapted to engage and move said stem in the opposite direction and to retain the valve in various adjusted positions against the action of the liquid pressure; and a valve-carrying member embodying a partition spaced from said transverse wall and having a central opening in which said valve stem is adapted to slide and also having a series of liquid passages, said valve-carrying member having an internal chamber behind said partition into which said inlet passage and said liquid passages open, communication between said liquid passages and said discharge orifice by way of such space being cut off by the engagement of the front end of the valve stem with said transverse wall.

3. An improved jet and spray producing nozzle or device comprising a valve having a hollow stem adapted to slide longitudinally in the direction of the liquid flow under the pressure of the liquid passing through the nozzle, said valve having an inlet opening to said stem at its rear end; an inlet passage aligning with said inlet opening and controlled by said valve; a manually operable adjusting sleeve enclosing said valve,

said sleeve having a central discharge orifice formed in alignment with said valve stem through a transverse front wall which is adapted to engage and move said valve stem in the opposite direction and to retain the 70 valve in various adjusted positions against the action of the liquid pressure; and a valve-carrying member embodying a partition having an opening wherein the valve stem is slidably arranged and also having a 75 series of liquid passages, said partition defining an internal chamber within the valve-carrying member into which said inlet passage and said liquid passages open and also defining a chamber between the front face 80 thereof and said transverse front wall, the liquid passages being disposed substantially tangential to the side wall of said front chamber.

4. An improved jet and spray producing nozzle or device comprising a valve having a hollow stem adapted to slide longitudinally in the direction of the liquid flow under the pressure of the liquid passing through the nozzle; an inlet passage aligning with said inlet opening and controlled by said valve; a manually operable adjusting sleeve enclosing said valve, said sleeve having a discharge orifice formed in alignment with the valve stem through a transverse front wall which is adapted to engage and move said stem in the opposite direction and to retain the valve in various adjusted positions against the action of the liquid pressure; a partition spaced from said transverse wall and having an opening wherein the valve stem is slidably arranged and also having a series of liquid passages formed through it, said partition defining a chamber behind it into which said inlet passage and said liquid passages open, communication between said liquid passages and said discharge orifice by way of such space being cut off by the engagement of the front end of the valve stem with said transverse wall; a valve seating formed at the rear of said partition; and a head on the rear end of said valve stem for coaction with said inlet passage and also adapted to engage said seating when the valve is in its foremost position, said valve stem having radial ports formed through it adjacent its head to provide communication between said chamber and the interior of the valve stem when such ports are open.

5. An improved jet and spray producing nozzle or device comprising a valve having a hollow stem adapted to slide longitudinally in the direction of the liquid flow under the pressure of the liquid passing through the nozzle; an inlet passage aligning with and controlled by the valve; a manually operable adjusting sleeve enclosing said valve, said sleeve having a discharge orifice formed in alignment with the valve stem through a

transverse front wall which is adapted to engage and move said stem in the opposite direction and to retain the valve in various adjusted positions against the action of the liquid pressure; a partition spaced from said transverse wall and having an opening wherein the valve stem is slidably arranged and also having a series of liquid passages formed through it, said partition defining a chamber behind it into which said inlet passage and said liquid passages open, communication between said liquid passages and said discharge orifice by way of such space being cut off by the engagement of the front end of the valve stem with said transverse wall of the adjusting sleeve; and a socket member wherein said liquid inlet passage is formed disposed behind said valve, said valve-carrying member being threaded to the forward end of said socket member while the rear end of the latter is threaded for connection to a hose director or supply pipe.

5 6 7 8 9 10 11 12 13 14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65

6. An improved jet and spray producing nozzle or device comprising a valve adapted to be moved in a forward direction by the pressure of the liquid passing through the nozzle; a manually operable adjusting sleeve enclosing said valve and adapted to move it in the opposite direction and retain it in various adjusted positions against the action of the liquid pressure; and a member at the rear of the valve formed with a liquid inlet passage and with a seating in its front face encircling the front end of such passage and adapted to be engaged by the rear end of said valve when the latter is moved to its rearmost position by said adjusting sleeve.

7. An improved jet and spray producing nozzle or device comprising a valve having a hollow stem adapted to slide longitudinally in the direction of the liquid flow under the pressure of the liquid passing through the nozzle, said valve having an inlet opening to said stem at its rear end; an inlet passage aligning with and controlled by said valve; a manually operable adjusting sleeve enclosing said valve, said sleeve having a central discharge orifice formed in alignment with said valve stem through a transverse front wall which is adapted to engage and move said stem in the opposite direction and to retain the valve in various adjusted positions against the action of the liquid pressure; a valve-carrying member embodying a partition spaced from said transverse wall and having a central opening in which said valve stem is adapted to slide and also having a series of liquid passages, said valve-carrying member having an internal chamber behind said partition into which said in-

let passage and said liquid passages open, communication between said liquid passages and said discharge orifice by way of such space being cut off by the engagement of the front end of the valve stem with said transverse wall of the adjusting sleeve; and a socket member wherein said liquid inlet passage is formed disposed behind said valve, said valve-carrying member being threaded to the forward end of said socket member while the rear end of the latter is threaded for connection to a hose director or supply pipe.

8. An improved jet and spray producing nozzle or device comprising an externally-threaded valve-carrying member having a central opening therethrough; a valve having a hollow stem slidably mounted in said opening and adapted to be moved forwardly by the pressure of the liquid passing through the nozzle, said valve having an inlet opening to said stem at its rear end; an inlet passage aligning with said inlet opening and controlled by the valve; and a manually operable, internally-threaded adjusting sleeve engaging the external thread of said valve-carrying member, said sleeve having a central discharge orifice formed in alignment with the valve stem through a transverse front wall which is adapted to engage and move said stem rearwardly and to retain the valve in various adjusted positions against the action of the liquid pressure; said valve-carrying member having a series of liquid passages which open at their front ends into a chamber between that member and said transverse sleeve wall and are disposed substantially tangential to the side wall of such chamber, and which open at their rear ends into a valve chamber behind the valve-carrying member and into which said inlet passage opens, whereby communication between said tangential passages and said discharge orifice will be cut off by the engagement of the front end of the valve stem with said transverse wall and the liquid will be ejected from said valve chamber through said hollow valve stem to the exclusion of said tangential passages, and the liquid may be ejected simultaneously through said tangential passages and valve stem when the transverse wall is disengaged from the front end of the valve stem.

9. An improved jet and spray producing nozzle or device comprising an externally-threaded valve-carrying member having a central opening therethrough; a valve having a hollow stem slidably mounted in said opening and adapted to be moved forwardly by the pressure of the liquid passing through the nozzle, said valve having an inlet opening to said stem at its rear end; a manually operable, internally-threaded adjusting sleeve engaging the external thread of said valve-carrying member, said sleeve having a cen-

tral discharge orifice formed in alignment with the valve stem through a transverse front wall which is adapted to engage and move said stem rearwardly and to retain the 5 valve in various adjusted positions against the action of the liquid pressure; said valve-carrying member having a series of liquid passages which open at their front ends into a chamber between that member and said 10 transverse sleeve wall and are disposed substantially tangential to the side wall of such chamber, and which open at their rear ends into a valve chamber behind the valve-carrying member, whereby communication between 15 said tangential passages and said discharge orifice will be cut off by the engagement of the front end of the valve stem with said transverse wall; a socket member, between which and the valve-carrying member 20 the valve chamber is located, having a central liquid inlet passage which opens into said valve chamber and which is disposed in line with said inlet opening and controlled by said valve, said valve-carrying member having an internal screw thread engaging an 25 external thread on the forward end of said socket member, the rear end of the latter being adapted for connection to a hose director or supply pipe; and an externally-threaded lock nut or ring freely surrounding said 30 socket member and engaging the rear portion of the internal thread of said adjusting sleeve.

10. An improved jet and spray producing nozzle comprising in combination an adjusting sleeve having at its front end a transverse wall provided with a central discharge orifice; a valve-carrying member housed within 35 said sleeve and having a series of liquid passages which establish communication between said discharge orifice and a liquid inlet passage of the device; and a longitudinally-sliding valve centrally disposed within

said valve-carrying member, said valve having a hollow or tubular stem the front end 45 of which is adapted to engage said transverse wall around said discharge orifice and thereby close the latter to the said series of liquid passages, said valve also having ports formed in it to establish independent communication 50 between said discharge orifice and said liquid inlet passage.

11. An improved jet and spray producing nozzle comprising in combination a socket member having a liquid inlet passage formed 55 centrally therethrough; a valve-carrying member screwed to the front end of said socket member and forming a valve chamber therewith, the forward portion of said valve-carrying member forming a partition 60 through which extends a series of passages; a valve longitudinally slidable within a central opening of said valve-carrying member in the direction of the liquid flow under the pressure of the liquid passing through the 65 nozzle, said valve having a head which is located within said valve chamber for movement between two opposite seatings which are engaged by said head in extreme 70 positions of the valve; said valve embodying a hollow stem having ports formed in it to establish communication between the valve chamber and the interior of the hollow stem; and a screw-threaded adjusting sleeve surrounding all the above-named parts and having 75 at its front end a transverse wall provided with a central discharge orifice, said wall being spaced from said partition to provide a front chamber into which said series of passages opens, said discharge orifice being 80 in alignment with the outer end of said hollow valve stem and having a diameter of less than the external diameter or width of said stem.

In testimony whereof I affix my signature.
FRED GLOVER.
